DESIGN FOR AN ELECTRIC CLOCK

Henry Triguba, New York, N. Y., assignor to
Joseph Gottlieb, Jersey City, N. J.

Application November 28, 1941, Serial No. 104,369

Term of patent 3½ years

To all whom it may concern:

Be it known that I, Henry Triguba, a citizen of the United States and a resident of the Borough of Bronx, county of Bronx, city and State of New York, have invented a new, original, and ornamental Design for an Electric Clock, of which the following is a specification, reference being had to the accompanying drawing, forming part thereof.

Figure 1 is a front elevational view of an electric clock showing my new design; and

Figure 2 is a side elevational view of the same.

I claim:

The ornamental design for an electric clock, as shown.

HENRY TRIGUBA.
